UNITED STATES PATENT OFFICE.

EDWIN S. VOTEY, OF DETROIT, MICHIGAN.

REED-ORGAN.

SPECIFICATION forming part of Letters Patent No. 374,721, dated December 13, 1887.

Application filed July 5, 1887. Serial No. 243,410. (No model.)

To all whom it may concern:

Be it known that I, EDWIN S. VOTEY, of Detroit, county of Wayne, State of Michigan, have invented a new and useful Improvement 5 in Reed-Organs; and I declare the following to be a full, clear, and exact description of the same, such as will enable others skilled in the art to which it pertains to make and use it, reference being had to the accompanying drawings, which form a part of this specification.

My invention relates to a certain new and useful improvement in organs, as more fully hereinafter set forth, and more particularly pointed out in the claims.

15 In the drawings, Figure 1 is a vertical cross-section of a reed-organ embodying my invention. Fig. 2 illustrates in separate views the fastening device.

The special feature of my invention consists 20 in the novel construction of the foundation-board and related parts of an organ, and which I carry out as follows:

A represents an organ-case.

A' is the organ-front, the whole of which I 25 prefer to make removable. Heretofore the upper part of the organ-front, and to which the "grand organ" and "knee-swell" have been attached, has very commonly been made permanent, the front below the same being removable. I design, however, to construct the entire "organ-front" with the grand organ and knee-swell, so as to be readily removed, as by a pin-and-dowel fastening, a, at the base and any suitable fastening, a', at the top.

35 B is the front rail of the organ action.

C represents any organ-action, the particular construction of which forms no feature of my present invention.

D is the foundation-board.

40 E is the air-chamber, and E' the valves controlling the admission of air to the reeds.

Heretofore great difficulty has been experienced in getting access to these valves and related parts should they get out of order, and 45 it is the special purpose of my invention to overcome this difficulty, so that it need not require an expert to clean the valve of any foreign substance or to make some needed adjustment of parts should they get misplaced.

50 I accomplish my purpose by dividing the foundation-board longitudinally thereof and

hinging the front portion, d, to the rear portion, d', in any suitable manner, so that the front may be dropped to get at the valves in a ready and convenient manner. The front 55 portion of the foundation-board thus constitutes a leaf hinged at its rear edge to the portion d'.

I do not limit myself to any manner of hinging the two together, but find it very convenient to tongue and groove the adjacent edges of the leaf and rear portion of the foundation-board, and to engage the same by hinges d² with or without a strip of felt or other fabric; but a strip of felt or fabric, d³, 65 is preferably secured upon the upper edge above the groove in the rear part of the foundation-board, to serve as a cushion. The front of the leaf closes against the front rail, B, of the action, to which it may be held in place 70 by any desired fastening, f. A very suitable method of fastening the same is by means of an angular-headed screw, f', or screw-lock engaged in the front rail, B, the leaf being grooved, as shown at f², to ride over the screw 75 f' when the latter is properly adjusted, the screw-head being turned under the foundation board or leaf, so as to support the same. The advantage of a screw for this purpose is in the fact that the screw may be readily adjusted to 80 tighten the engagement of the leaf upon the rail, while at the same time it affords a very simple fastening.

With an organ provided with my improved foundation-board access to the valves is rendered easy. The organ may be laid upon its back, the front board, with its attachments, removed, when the leaf may be dropped and the necessary adjustment or cleansing of the valve be quickly accomplished without employing a skilled workman to give the matter 85 attention.

While the feature of providing a hinged or removable leaf in the foundation-board opposite the valves is always desirable, whether 95 the action be a horizontal action or a vertical action, it is especially desirable in organs provided with a horizontal action, because in organs of this character the space beneath the foundation-board is occupied by the organ-front and the pedal mechanism, so that the removal of the board itself becomes practically 100

impossible. Heretofore in organs with a horizontal action access to the valve has been possible only by first removing all the mechanism of the organ which is situated above the valves. By my invention, however, the valves in an organ provided with the horizontal action may be readily exposed by dropping the leaf, and without disturbing any of the other parts. So, also, in an organ with a vertical action my invention enables any unskilled person to at once expose the valves by dropping or removing the removable leaf, whereas it would involve considerable trouble and annoyance to be compelled each time to remove a considerable number of fastening-screws in order to take off the entire foundation-board in this class of organs. This is especially true where the leaf is simply fastened by a screw, hook, or other similar expedient, which may serve to release the removable lid and permit it to be opened instantly in case of emergency. The feature of the removable front is especially valuable, also, in a horizontal-action organ provided with my removable front leaf, because, having laid the organ on its back and having removed the leaf of the foundation-board to gain access to its valves, the organ-front with its knee-boards would be in the way of the operator, and would interfere with the dropping of the front leaf, and also liable to become marred; but by removing the same the operator can proceed to adjust the valve mechanism with greater freedom and ability.

What I claim is—

1. In an organ, a foundation-board constructed with a leaf constituting a part of the foundation-board arranged to be opened, and thereby afford access to the interior, substantially as described.

2. In an organ, a foundation-board constructed with a hinged leaf constituting a part of the board, and a detachable fastening device to hold the leaf in place, substantially as described.

3. The combination, with a horizontal-action organ provided with a front rail, B, of a foundation-board constructed with a front leaf arranged to be opened to afford access to the interior, and a screw-hook engaged in said rail to support said leaf and tighten it on its seat, said leaf constructed with open orifices or grooves upon its front edge to receive the stem of said hook, substantially as described.

4. The combination, in an organ, of a foundation-board provided with a removable leaf constituting a part of the board, said removable leaf located opposite the valves and secured in place by detachable fastenings, the construction being such that access may be had to the valves without removing or disturbing the fastenings of the foundation-board, substantially as and for the purpose described.

5. The combination, with a horizontal-action organ, of a foundation-board constructed with a front leaf arranged to be opened and afford access to the interior, and an organ-front extending upward to the foundation-board, the entire said front being removable, substantially as described.

In testimony whereof I sign this specification in the presence of two witnesses.

EDWIN S. VOTEY.
